UNITED STATES PATENT OFFICE

ALVA H. SCHICK AND RANDOLPH P. KRAATZ, OF OMAHA, NEBRASKA

DESIGN FOR A CLOCK CASE

Application filed April 18, 1932. Serial No. 43,536. Term of patent 7 years

To all whom it may concern:

Be it known that we, ALVA H. SCHICK and RANDOLPH P. KRAATZ, citizens of the United States, residing at Omaha, in the county of Douglas and State of Nebraska, have invented a new, original, and ornamental Design for a Clock Case, of which the following is a specification, reference being had to the ac-

companying drawing, forming a part hereof.

The figure is a perspective view of a clock case, showing our new design.

We claim:

The ornamental design for a clock case, as shown.

ALVA H. SCHICK.
RANDOLPH P. KRAATZ.
